NOZZLE

Robert C. Lawrence, Sr., 708 Bubbling Well, Glendora, Calif. 91740, and Robert C. Lawrence, Jr., 1943 Barrington Court, Claremont, Calif. 91711

Filed July 18, 1969, Ser. No. 18,277

Term of patent 14 years

Int. Cl. D23—01

U.S. Cl. D23—34

FIG. 1.

FIG. 2.

FIG. 3.

FIG. 4.

FIG. 5.

FIG. 6.

FIG. 1 is an isometric view of a nozzle, showing our new design;

FIG. 2 is an isometric view of a nozzle, this view being taken from a position opposite from that of the view of FIG. 1;

FIG. 3 is a top view thereof;

FIG. 4 is an elevational view thereof;

FIG. 5 is an end view thereof; and

FIG. 6 is an end view showing the end opposite that shown in FIG. 5.

We claim:

The ornamental design for a nozzle, as shown.
